UNITED STATES PATENT OFFICE.

THOMAS HENRY EDMONDS, OF WASHINGTON, DISTRICT OF COLUMBIA.

SEPARATING-SCREEN.

SPECIFICATION forming part of Letters Patent No. 586,724, dated July 20, 1897.

Application filed March 18, 1896. Serial No. 583,784. (No model.)

To all whom it may concern:

Be it known that I, THOMAS HENRY EDMONDS, a citizen of the United States, and a resident of Washington, District of Columbia, have invented a new and useful Separating-Screen, of which the following is a specification.

My invention relates to that class of screens which are inserted in water-supply pipes, and is more particularly intended for use in connection with the pipes of automatic valve-regulators. It is, however, adapted to be used in any water-supply pipe where it is desirable to keep lint, scale, shell, or any foreign substance whatever from passing through the pipes.

My invention consists in the subject-matter hereinafter described and more specifically pointed out in the claim.

Referring to the drawings which form a part of this application, Figure 1 is a side elevation of the supply-pipe provided with inflow and outflow valves and having my improved screen-chamber located therein. Fig. 2 is a vertical section through the center of the screen-chamber, showing the screen in position therein. Fig. 3 is a perspective view of my improved screen removed from the chamber.

In the drawings, A indicates a water-supply pipe having located therein the inflow and outflow valves B B. Suitably located between these valves is the screen-chamber C. This screen-chamber has a suitable slot or recess G cut therein, and in this slot or recess is placed a screen, which is hereinafter more fully described.

The screen proper consists of two apertured framing-plates E E, united detachably by screws e or in any other suitable manner. By firmly clamping the wire fabric between the two apertured plates I form an exceedingly solid structure and one adapted to be used in pipes in which very high pressure of water is maintained. In screens with which I am familiar the trouble heretofore has been that when any considerable amount of sediment of any description had collected upon

or behind the screens the pressure of the water would force them from their fastenings. As the parts of my screen are assembled before it is placed in the pipe it is possible to cause the apertured framing-plates to grip the wire fabric with such force that it cannot be pulled out from between them, and when the framed screen is seated in the groove in the pipe it will of course remain in place, no matter how great the pressure of the water may be. Again, as the apertured plates are detachably united should the wire fabric become worn it is an exceedingly simple matter to replace it.

In the construction of my device when the parts of the screen have been assembled, as hereinbefore indicated, the screen is slid into the recess G in the valve-chamber C, and then the plug or bonnet D is screwed firmly down into position on top of the screen. The plug or bonnet not only serves to close the opening through which the screen is introduced, but also serves to hold the screen in place and to prevent fluid from passing through the pipe otherwise than through the screen.

It will be noted that my improved screen is exceedingly simple in construction. It can be instantly removed from the screen-chamber by closing the inlet-valve and unscrewing the plug or bonnet D. Should the pipe become choked in any manner, therefore, the operation of cleaning it can be performed expeditiously and with very little trouble.

What I claim is—

In a separating-screen, the combination with a casing having a passage therethrough and provided with a recess transverse to the passage, of a screen adapted to fit in said recess and composed of two apertured framing-plates detachably secured together, and having a wire fabric firmly clamped between them, all substantially as and for the purpose set forth.

THOMAS HENRY EDMONDS.
